SIGN

**Irving Nachumsohn, Chicago, Ill., assignor to
Naxon Corporation, Chicago, Ill., a corporation
of Illinois**

Application June 29, 1929, Serial No. 374,631

10 Claims. (Cl. 177—346)

This invention relates broadly to improvements in the construction and method of operation of luminous advertising or display signs, and in the present instance more specifically to the aforementioned features of signs comprised, wholly or in part, of gaseous conduction lamps.

While for the sake of clarity, my illustration and description are exemplary of the application of my invention to a luminescent tube sign, it will be readily manifest that the invention can be advantageously used in connection with many other types of luminous devices, and therefore has a wide field of utility.

15 It will be further understood that variations in the design, construction and application of my invention may be resorted to without departing from the spirit of the invention, and I do not mean to limit myself in this respect, except as I may do so in my claims.

20 In an advertising sign displaying a permanent message in connection with a decorative design in the form of a border or the like, it is usually preferable to confine any effect of motion or flashing to the decorative portion, and to keep
25 the message portion constantly illuminated, in order that the eye of the observer may be attracted by said border, but not interrupted during the perusal of the message. I have, therefore, shown and will describe an embodiment of my
30 invention in which the message of the sign takes the form of a permanent word, illuminated by lamps or painted on a background of contrasting color, while the aforementioned moving or wave effect is confined to the decorative embellishments of the sign. Said moving effect represents, in the present instance, the flickering, or scintillous, effect in addition to the building-up or spreading of a flame; but since the dominating optical effect is essentially a wave motion it is
35 obvious that this invention can be modified, by rearranging the luminescent tubes for example, to represent analogous wave motion of water, smoke, etc.

The primary objects of my invention are the provision of an arrangement of illuminatable elements and means for controlling the illumination of same in such a way that a predetermined moving effect is produced; the provision of an arrangement of the lamps, such as gaseous conduction tubes, comprising the sign which will cause the moving effect to take the form of radiating or travelling waves of light; and the provision of a secondary means of controlling the illumination of said lamps to produce a building-up or spreading of the illuminated area of the sign.

In my copending applications for U. S. Letters Patent Serial Nos. 289,586 and 375,196 which matured into Patents Number 1,913,504 and Number 1,913,505, respectively, granted June 13, 1933, I have shown arrangements whereby light effects may be produced which appear to travel lengthwise of the gaseous conduction tubes employed as the illuminating elements. Such disclosures however, refer to comparatively simple variable light effects while one object of the present invention is to provide an arrangement whereby a plurality of different light effects may be economically coordinated in a large commercial sign. 10

Furthermore, while my co-pending application for Letters Patent Serial No. 342,144 which matured into Patent Number 1,984,939, granted December 18, 1934, discloses a method of producing interrupted and fading light effects among gaseous lamps without the use of electrical switches, variable resistors or circuit-interrupting devices, where it is desirable or not objectionable to employ such devices the present invention discloses an arrangement for doing this in a large outdoor sign without necessarily complicating such switching apparatus. . . .

The foregoing and other objects and advantages will be disclosed in the following description and the accompanying drawing, in which

Fig. 1 is a more or less diagrammatic view of a sign embodying the improved features of my invention, and

Fig. 2 is a schematic diagram of the electrical circuit and controlling system of same.

Referring now to the drawing, and particularly to Fig. 1, it will be observed that the sign 6 comprises the word "Naxon" the letters of which are designated by the numeral 3; a decorative border, the vertical portion of which I have indicated by the numeral 4; and the upper horizontal portion by 5. The vertical border 4 is in turn composed of six sections or banks of illuminatable tubes 11, 12, 13, 14, 15 and 16. The top border 5 is composed of six banks of lamps 21, 22, 23, 24, 25 and 26. Each of these two groups consists of three tubes as indicated at 16^a, 16^b, and 16^c of group 16, and at 26^a, 26^b and 26^c of group 26. It will also be observed that the upper or horizontal border 5 has its tubes arranged in the form of a flame, each of the six sections taking the irregular shape of a separate tongue of flame, and that the tubes comprising the vertical border 4 are also bent in irregular shapes, but are at the same time confined to form a comparatively narrow band along the side of the sign.

All of the tubes in Fig. 1 have been indicated 55

diagrammatically by single heavy lines, to improve the clarity of the drawing. In Fig. 2 these tubes have been shown in conventional schematic form and can be seen to have darkened or opaque portions 7 distributed throughout their length either at regular or irregular intervals, the spacing and arrangement of the covered portions 7 depending upon the form that it is desired to have the effect of motion take. When the opaque sections 7 are regularly spaced and staggered as shown in the groups of tubes 11, 12, 13, 14, 15 and 16 comprising the side border 4, the effect produced by the consecutive illumination, one at a time, of the three tubes of one section, is that 15 of a series of alternate light and dark bands all moving together along the tubes, their direction being determined by the sequence in which the three tubes are illuminated. When the darkened portions 7 are irregularly spaced and not uniformly staggered in their arrangement, as in the lamps comprising the horizontal border 5, and the tubes are alternately lighted, the effect produced is a flamelike flickering of the light, the exact character of which depends upon the spacing and arrangement of the opaque portions and the order in which the tubes are lighted.

In Fig. 2 the conductors 8 and 9 are connected to the power supply circuit which may be any suitable source of 60 cycle alternating current. 30 The conductor 8 connects one side of the line with the commutators 31, 32, 33, 34, 35 and 36 through the commutator shaft 10, which may be driven in any suitable manner, in the direction indicated by the arrow. The conductor 9 connects the other side of the line to the primaries of the coupling transformers 41, 42, 43, 44, 45 and 46. The transformer primary circuits are intermittently completed through the brushes 17 which make contact with the commutators 31, 32, 33, 34, 35 and 36. The high-potential secondaries of the transformers 41, 42, 43, 44, 45 and 46 are connected on one side through the common conductor 18 and one end of each of the gaseous conduction lamps comprising the border 5, and on their other sides to separately insulated sections of the distributor shaft 19; the secondary of transformer 41 connecting with section 51, the secondary of 42 with section 52, the secondary of 43 with section 53, the secondary 44 with the section 54, the secondary 45 with the section 55 and the secondary 46 with the section 56 of the shaft 19. Contact arms, or brushes, 51^a, 52^a, 53^a, 54^a, 55^a and 56^a, attached to sections 51, 52, 53, 54, 55 and 56 respectively move over and make successive contact with the three segments on each of the distributor supports 51^b, 52^b, 53^b, 54^b, 55^b and 56^b, which segments are in turn connected with one end of the tubes of the vertical border 4. The tubes of the border 4 are connected in series with the tubes of the border 5 in such manner that when group 11 is lighted group 21 also lights; when group 12 is lighted 22 lights with it; and so on throughout the entirety of borders 4 and 5. 65 As is plainly manifest from Fig. 2, the respective brush arms 51^b, 52^b, 53^b, 54^b, 55^b and 56^b are each made wide enough to span two of the contact segments in order that rotation thereof will cause the closing of one of the three tube circuits before breaking the circuits including the tubes previously illuminated. In this respect and for the same purpose, it may be noted that said brush arms and contact segments are constructed identically to the brush 11 and segments 3', 4'

and 5' shown in Fig. 2 of the application Serial No. 375,196 above referred to.

The operation is as follows: when shaft 10 is rotated it rotates shaft 19 through the medium of the belt 20 and the pulleys 21 and 28. The commutators 31, 32, 33, 34, 35 and 36 are provided with insulated segments 29, the angular length of which is such that transformers 41, 42, 43, 44, 45 and 46 are successively connected and maintained in connection with the power source, thereby successively lighting the banks of tubes 11 and 21, 12 and 22, 13 and 23, 14 and 24, 15 and 25, and last 16 and 26. This causes the border 4 to gradually extend itself down the side of the sign and the upper border 5 to build up and increase in area across the top of the sign from left to right. The commutators on the shaft 10 maintain both of the borders 4 and 5 in the lighted condition for a time and then extinguish all of the lamps in both borders simultaneously, whereupon the building up process is again begun. While the foregoing cycle is in progress, the distributor segments on 51^b, 52^b, 53^b, 54^b, 55^b and 56^b cause the three tubes in each of the banks to be lighted consecutively, one at a time, and thereby produce the effect of a moving or flickering light, as the case may be, in all of the banks that the commutators on shaft 10 have caused to be illuminated. By virtue of the great difference in diameter between the pulleys 27 and 28 the shaft 19 makes several revolutions while the shaft 10 rotates once, with the obvious result that the effect of flicker or motion appears to be independent of the building up effect. It will be found that best results are obtained by operating the shaft 19 from 1½ to 4, or at most 5, revolutions per second.

It is apparent that there are two different yet effectively combined moving light effects displayed. One, the building-up or spreading effect 40 caused by the cumulative or aggregated illumination of the groups of tubes and the secondary effect caused by the three tubes of each group being successively illuminated. Moreover, the first named effect is produced by switching means 45 connected in the primary or low voltage circuits of the tube transformers while the second named effect is obtained by means connected in the secondary or high voltage circuits of the transformers. It will also be noted that notwithstanding the large number of tubes employed and the combination of a plurality of different moving light effects, the arrangement is such as to require only six transformers for supplying the necessary high voltage ionizing current to all of 55 the tubes. This arrangement is highly desirable and therefore of great importance, inasmuch as the tube transformers are costly and parallel operation of columnar gaseous conduction lamps is difficult because of their inherently high resistance, as explained in my application Serial No. 375,196 heretofore referred to. In the arrangement shown and described parallel connection of the tubes is unnecessary and while I have shown the tubes in Fig. 2 relatively short it will readily 60 occur that they may be of any desirable length and that each single tube may be substituted by a plurality of tubes connected in series thereby permitting the use of a much greater number of individual tubes without necessitating parallel 65 connection thereof or without increasing the number of transformers.

I claim:

1. In a display system of the class described, the combination of a plurality of groups of

5 eous illuminating elements, a transformer having a primary and a secondary winding for each group for supplying operating current thereto, a controlling device in a circuit including the secondary winding of each transformer for operating said elements of the corresponding group to produce a certain light display, within the group, a controlling device in a circuit including the primary winding of each transformer for operating 10 the corresponding group of elements, and means for co-ordinating the operation of said last named controlling devices to produce a light display among the groups of elements.

15 2. In a display system of the class described, the combination of a plurality of groups of gaseous illuminating elements, a transformer for each group for supplying operating current thereto, a controlling device in a circuit including the secondary winding of each transformer for operating 20 said elements of the corresponding group to produce a certain light display within the group, a controlling device in a circuit including the primary winding of each transformer for operating the corresponding group of elements 25 and a common actuating means for said last mentioned controlling devices arranged to coordinate their operation to produce a light display among the groups of elements.

30 3. In a display system of the class described, a plurality of groups of illuminating members arranged to produce a plurality of variable light effects, a transformer common to said members of a group for supplying current thereto, means in the secondary circuit of each of said transformers for operating said members to produce certain of said light effects, and means in the primary circuits of said transformers for energizing said transformers cumulatively to produce an over-all light effect among the groups.

35 40 4. In a display system of the class described, a plurality of groups of illuminating members arranged to produce a plurality of variable light effects, a transformer common to said members of each group for supplying current thereto, means in the secondary circuit of said transformer for operating said members to produce certain of said light effects, means in the primary circuits of said transformers for energizing said transformers cumulatively to produce another of 45 said light effects, and a common operating member for both of said operating means.

45 5. In a display system of the class described, the combination of a plurality of groups of illuminating elements, a transformer for each group 50 for supplying current thereto, a controlling device in the secondary circuit of each transformer for operating said illuminating elements at a given rate, a controlling device in the primary circuit of each transformer for operating said illuminating 55 elements at a different rate, and means for operating said first-named controlling devices all in unison at one rate and for operating said second-named controlling devices at a different rate.

60 65 6. In a sign controlling device of the character described, the combination of a plurality of groups of gaseous discharge lamps, a transformer for each group having a secondary winding in a circuit in which said lamps are included, a controlling device for said circuit, means co-ordinating the operation of said controlling devices 70 for operating said lamps in predetermined se-

5 quential relation, each of said transformers having a primary winding in a circuit connected to the source of power, a primary controlling device in each transformer primary circuit, and means co-ordinating the operation of said primary controlling devices in predetermined sequential relation.

7. In a sign controlling device of the character described, the combination of a plurality of groups of gaseous discharge lamps, a transformer 10 for each group having a secondary winding in a circuit in which said lamps are included, a controlling device for said circuit, means co-ordinating the operation of said controlling devices for operating said lamps in predetermined sequen- 15 tial relation, each of said transformers having a primary winding in a circuit connected to the source of power, a primary controlling device in each transformer primary circuit, means co-ordinating the operation of said primary con- 20 trolling devices in predetermined sequential relation, and means co-ordinating the operation of said first named controlling devices with relation to the operation of said primary controlling devices. 25

8. In a sign controlling system of the class described, the combination of a plurality of groups of gaseous discharge lamps, a transformer for each group comprising a primary and a secondary winding, a controlling device for each group 30 arranged to connect the lamps of the group with the transformer secondary associated with said group in a predetermined sequential relation, means co-ordinating the operation of the several controlling devices with relation to each other, 35 a controlling device for the primary winding of each transformer, and means co-ordinating the operation of the said secondary controlling devices with the operation of said primary controlling devices. 40

9. The combination with a plurality of gaseous conduction lamps and a plurality of step-up transformers for supplying ionizing potential thereto, of a plurality of potential distributors in the respective secondary circuits of said trans- 45 formers and operable in unison at a given speed for the production of a given variable light effect; a plurality of current distributors in the respective primary circuits of said transformers operable in unison at a relatively low speed for the 50 production of a relatively slow variable light effect, and means for correlating said variable light effects and common to said potential and current distributors for operating the same.

10. The combination with a plurality of groups 55 of illuminating elements, of a transformer for each group for supplying current thereto, a controlling device in the secondary circuit of each transformer comprising a stationary contact segment for each illuminating element within a 60 group and a common rotatable member for successively energizing said illuminating elements of said group through said segments, a controlling device in the primary circuit of each trans- 65 former, means for co-ordinating the operation of the respective controlling devices associated with the primary and secondary circuits of each trans- 70 former in a predetermined relation to operate said illuminating elements to produce various display effects. 70

IRVING NACHUMSOHN.
